UNITED STATES PATENT OFFICE.

ALEXANDER PONIATOWSKI, OF PERTH AMBOY, NEW JERSEY.

SOLDIER'S SHIELD.

1,267,588.

Specification of Letters Patent. Patented May 28, 1918.

Application filed March 11, 1918. Serial No. 221,701.

To all whom it may concern:

Be it known that I, ALEXANDER PONIATOWSKI, a citizen of Russia, residing at Perth Amboy, in the county of Middlesex and State of New Jersey, have invented certain new and useful Improvements in Soldiers' Shields, of which the following is a specification.

The primary object of the invention is the provision of a shield for soldiers in the nature of a portable barrier for protecting soldiers from the bullets of the enemy when engaged in battle, the device being readily transported when desired and possessing great strength and stability when set up for use.

A further object of the device is to provide a bullet shield serviceable as a cart or ambulance when not in use as a shield, the device being suitably retained in either of its adjusted positions as a cart or a barrier.

A still further object of the device is the provision of a wheeled bullet shield permitting soldiers to fire upon the enemy when protected by the shield and providing a form of firing booth for accommodating the soldiers during an engagement with the enemy.

In the drawing forming a part of this application and in which like numerals refer to corresponding parts throughout the several views:

Figure 1 is a vertical sectional view of the device taken upon line 1—1 of Fig. 2, the arrangement of the shield when employed as a cart being illustrated by dotted lines;

Fig. 2 is a rear elevational view thereof, parts being broken away;

Fig. 3 is a detail view partially in section illustrating the retaining means in its operative arrangement with the device employed as a cart; and

Fig. 4 is a similar detail view partially in section upon line 4—4 of Fig. 2 with the device employed as a bullet shield.

Referring more in detail to the drawing, the device broadly consists of an armor plate 10 substantially rectangular in form having a curved portion 11 at one longitudinal edge thereof, the said plate being formed of bullet-proof material adapted as a shield for soldiers positioned behind the same with the curved portion 11 disposed at the top of the device and extending rearwardly for service in deflecting oncoming bullets.

Substantially A-shaped brackets 12 are secured to the rear side of the plate 10 having bearings 13 at their rear converging ends with a shaft 14 journaled in the said bearings 13 and having ground wheels 15 journaled upon the shaft 14 adjacent its opposite ends and outwardly of the brackets 12.

Arms 16 are secured to the shaft 14 provided with heads 17 upon their free ends normally positioned upon the ground such as 18 when the device is set up for use as a barrier with the plate 10 vertically disposed. A spring-pressed bolt 19 is carried by the cross-piece 20 of each of the brackets 12 for seating within sockets 21 in the adjacent side of the shaft 14 when the plate 10 is disposed vertically as shown in Fig. 1 of the drawing, said bolts 19 being also adapted for seating within similar sockets 22 in the shaft 14, when the plate 10 is horizontally positioned for use as a cart as illustrated in Fig. 3.

Port-holes 23 are provided in the plate 10 through which the soldiers located behind the barrier may readily shoot at the enemy. A counter or platform 24 is provided on the rear side of the said plate providing trays 25 for holding ammunition for the accommodation of the soldiers. It will be understood that when the plate 10 is horizontally disposed and locked in position by means of the bolt 19, the arms 16 may be grasped by the soldier and the device readily pushed or drawn along to the desired position for setting up as a bullet-protecting shield while articles for soldiers may at such times be positioned upon the horizontally arranged plate 10 for purposes of transportation if desired. When the plate 10 is vertically disposed and the bolts 19 are locked within the recesses 21, the device will present a rigid arrangement as the bottom of the plate 10 rests upon the ground 18 as does also the wheels 15 and the heads 17 of the arms 16, which arms are rigid with the said shaft 14.

A serviceable arrangement for soldiers is provided adapted for preventing loss of life as well as a portable barrier or wall wherever the same may be desirable, and being convertible into a cart presents a large platform which may be employed for many different purposes.

What I claim as new is:—

1. A shield comprising a plate having port-holes therethrough, a wheeled shaft, brackets upon said plate journaled upon said

shaft, locking connections between the said brackets and shaft operable with the plate in either its horizontal or vertical position, and arms rearwardly projecting from the shaft with their free ends positioned upon the ground when the plate is arranged upright as a bullet shield with its lower edge contacting the ground.

2. A device of the class described comprising a shaft, ground wheels journaled upon the shaft adjacent its opposite ends, positioning arms secured to the shaft having their free ends normally engaging the ground, an armored plate having a rearwardly curved edge and provided with port-holes, substantially A-shaped brackets upon the rear side of the plate journaled upon said shaft, spring-pressed bolts carried by the brackets adapted for locking engagement with the shaft when the plate is in either its horizontal position with the device arranged

as a cart or in its vertical position as a bullet shield.

3. In combination with a sheet metal plate having port-holes therethrough and a rearwardly curved bullet-deflecting edge, a shaft, ground wheels journaled upon the shaft, brackets carried by the plate journaled upon the said shaft, locking bolts carried by the brackets, the said shaft having spaced sockets therein adapted for the reception of the said bolts when the plate is in either its horizontal or vertical arrangement, ammunition-holding means carried by the rear side of the plate beneath the said holes, and rearwardly projecting arms secured to the shaft having heads at their free ends normally positioned upon the ground when the device is in use as a shield.

In testimony whereof I affix my signature. 40

ALEXANDER PONIATOWSKI.
